PANELBOARD LOCKING MEANS**

William Harold Edmunds, Havertown, Pa., assignor to
I-T-E Circuit Breaker Company, Philadelphia, Pa., a
corporation of Pennsylvania

Filed Aug. 31, 1960, Ser. No. 53,309
6 Claims. (Cl. 317—119)

The instant invention relates to panelboards and more particularly to a novel panelboard construction whereby a circuit breaker of a given width may be replaced by a pair of circuit breakers which together occupy the same width.

In recent years it has been the practice to construct panelboards for home and light industrial applications in a manner such that the panelboards are adapted to receive circuit breakers whose widths are one inch or multiples thereof. More recently half inch wide circuit breakers have made their appearance on the market. While panelboards may be constructed specifically to utilize breakers of half inch width, it is highly desirable to utilize panelboards which are adapted for either breakers of one inch width or one-half inch width.

The prior art utilizes existing panelboards with narrow type circuit breakers by positioning two independently operable circuit breaker units in a single wide housing and providing a common line terminal for both circuit breaker units. With this arrangement, if there is a mechanical or electrical failure in one of the circuit breaker units a replacement of the unit at fault entails the replacement of two circuit breaker units. Further, in the original construction of the circuit breaker the ratings of the pole units must be established. That is, once the circuit breaker units are mounted within the single housing, if the rating of one circuit is changed then an entirely new circuit breaker comprising two poles must be changed.

In order to overcome the problems outlined above, the Leonard et al. copending application, Serial No. 18,411, filed March 29, 1960, now Patent Number 3,095,524, entitled "Panelboard Adapter," and assigned to the assignee of the instant invention, provides a line terminal adapter means which electrically connects two narrow circuit breakers each of which is provided with its own housing. The adapter means may be placed between two circuit breakers to achieve a duplex breaker or may be placed on either the right or left side of a single breaker, so that this breaker may be utilized individually in the panelboard. Extreme flexibility is achieved in that there are two separate and independent circuit breakers which can be tied together in any combination of ratings after the individual circuit breakers are completed.

The adapter means is primarily intended to provide an electrical connection. However, the adapter means often provides the only mechanical connection between the circuit breakers. Thus, it is necessary to provide some means for holding the circuit breakers together at their load sides. The conventional mounting hook for one inch circuit breakers cannot be utilized if the half inch circuit breakers are to be of identical construction, with one exception. That is, the mounting recess of the half inch breaker may extend the full width thereof, so that when two half inch breakers are placed side by side there is in effect a single wide recess. It is most desirable that the external portions of the circuit breakers be of identical construction to reduce the number of different parts required and to enable any breaker to be mounted at any panelboard location if the rating of the breaker offers proper protection for the branch circuit in question.

The open ended mounting recess arrangement gives rise to two major problems, namely, the circuit breaker combination is not held in a central position with respect to the mounting hook, nor is the load side of the circuit

2

breaker combination held together. If the load side of the combination is not held together, it is possible to spread the line side adapter means thereby adversely affecting the line side electrical connections.

The instant invention solves the previously noted problem by providing a panelboard mounting hook which includes a central notch thereby effectively subdividing each hook into two portions. When it is desired to mount a one inch wide breaker to the panelboard, the mounting recess of the one inch wide breaker receives both portions of the mounting hook. When a pair of half inch wide breakers are mounted in place of the one inch wide breaker, each portion of the panelboard mounting hook is received by an individual recess of the circuit breakers. With this arrangement the mounting recesses of the half inch wide circuit breakers may be closed at the ends thereof. The closed-ended mounting recess assures that the circuit breakers are held in a substantially fixed position so that the possibility of spreading the line terminal adapter is eliminated.

Accordingly, a primary object of this invention is to provide a novel arrangement whereby a pair of narrow circuit breakers may be installed in a panelboard in place of a wide circuit breaker.

Another object is to provide a panelboard of novel construction whereby a pair of narrow circuit breakers of identical external constructions may be mounted in place of a single wide circuit breaker.

Still another object is to provide a novel panelboard construction whereby either one inch or half inch wide circuit breakers may be mounted with the load ends thereof substantially fixed in position.

A further object is to provide a novel panelboard having mounting hooks which are centrally notched so that a pair of half inch wide breakers of identical construction may be securely mounted in place of a one inch wide breaker.

These as well as other objects of this invention shall become readily apparent after reading the following description of the accompanying drawings in which:

FIGURE 1 is a perspective of a prior art panelboard illustrating the mounting of one inch wide circuit breakers thereto.

FIGURE 2 is an end view of one of the wide circuit breakers of FIGURE 1.

FIGURES 3 and 4 are end views of a pair of narrow circuit breakers constructed to be mounted to the panelboard of FIGURE 1.

FIGURE 5 is an end view of a pair of narrow circuit breakers of identical construction which cannot be mounted to the panelboard of FIGURE 1.

FIGURE 6 is a fragmentary perspective of a panelboard housing whose mounting ledge is provided with hooks constructed in accordance with the teachings of the instant invention, whereby the circuit breakers of FIGURE 5 may be mounted thereto.

FIGURE 7 is a fragmentary view taken through section 7—7 of FIGURE 5 looking in the direction of arrows 7—7 and showing the relationship between the notched mounting hook of FIGURE 6 and the mounting recesses of the half inch circuit breakers of FIGURE 5.

Now referring to the figures, and more particularly to FIGURE 1 which illustrates prior art panelboard 10. This panelboard 10 comprises base 11, having walls 12, 13 at opposite edges thereof, and insulating mounting block 14 mounted between walls 12, 13. Mounting block 14 is provided with suitable recesses, as is well known to the art, to maintain bus bars 15, 16 in operative positions extending parallel to the walls 12, 13. Mounting block 14 also maintains male stabs 17—19 aligned in a row extending parallel to bus bars 15, 16. As is well known to the art, stabs 17—19 are electrically

connected to appropriate ones of the bus bars 15, 16 so that when bus bars 15, 16 are electrically energized stabs 17-19 are also energized.

Each of the walls 12, 13 is provided with a mounting ledge 20 which is secured in place by screws 21. Each mounting ledge 20 is provided with a suitable recess 22 which receives an extension 23 of mounting block 14 to maintain mounting block 14 in a fixed position relative to base 11.

Mounting ledge 20 is provided with a plurality of spaced mounting hooks 25 whose free ends extend toward stabs 17-19. There is a mounting hook 25 on each of the mounting ledges 20, which is positioned in alignment with individual ones of the stabs 17-19 so that each stab is positioned to energize circuit breakers extending from both walls 12 and 13.

For mounting of circuit breaker 26 to panelboard 10 the mounting recess 27 at the load end of circuit breaker 26 is moved until it receives one of the mounting hooks 25. Thereafter the line end 28 of circuit breaker 26 is pivoted toward stabs 17-19 with hook 25 acting as a pivot point. The jaws of circuit breaker line terminal 29 engage the one of the stabs 17-19 which is aligned opposite the mounting hook in question.

It is to be noted that mounting recess 27 is closed at the ends thereof and that the width of this mounting recess is only slightly greater than the width of mounting hook 25. With this arrangement the load end 29 of circuit breaker 26 is maintained against movement transverse to the plane in which breaker 26 is pivoted into engagement with the male stab.

In FIGURE 3 there is illustrated a pair of half inch circuit breakers 30, 31 mounted in adjacent side by side relationship. In this arrangement the mounting recesses 32, 33 of circuit breakers 30, 31, respectively, are each open at only one of the ends thereof. Thus, with circuit breakers 30, 31 mounted as shown, recesses 32, 33 communicate with one another to form a single recess, which is as wide as recess 27, so that the combination of breakers 30, 31 may be mounted to panelboard 10 in place of one of the circuit breakers 26.

It is to be noted that the bases 34, 35 of circuit breakers 30, 31, respectively, are of different constructions and that the covers 36, 37 of circuit breakers 30, 31, respectively, are also of different constructions. This is highly undesirable and impractical from the manufacturing standpoint as it requires the stocking of many different parts.

In addition, with this arrangement circuit breaker 30 cannot be mounted in combination with circuit breaker 31 while mounted to the left thereof with respect to FIGURE 3. Further, since mounting recesses 32, 33 are each open at one of the ends thereof, mechanical securing means are required at the load ends of breakers 30, 31 to prevent these breakers from spreading apart and adversely affecting the electrical connections with stabs 17-19.

FIGURE 4 illustrates an arrangement for utilizing two identical half inch circuit breakers 40 in combination in the prior art panelboard 10. In this arrangement the mounting recess 41 of circuit breaker 40 extends the full width thereof and is not closed at either end. With this arrangement the combination of two circuit breakers 40 is not held in a central position with respect to mounting hook 25, nor is the load end of circuit breaker 40 held in substantially fixed position. Thus, circuit breaker 40 is not held against movement transverse to the plane in which circuit breaker 40 is pivoted during mounting thereof.

FIGURE 5 illustrates a pair of identical circuit breakers 45 mounted in adjacent side by side relationship. Each of the circuit breakers 45 is provided with a mounting recess 46 which is closed at both ends thereof. In order to accommodate a combination of two circuit breakers 45, a panelboard having mounting ledge 50

(FIGURE 6) must be utilized. Mounting ledge 50 replaces mounting ledges 20 of panelboard 10 and in all other respects the panelboard 90 is the same as panelboard 10.

Mounting ledge 50 includes hooks 51, each having a width A which is the same as the width of hook 25 so that the entire hook 51 may be received in mounting recess 27 of a wide circuit breaker 26. Each hook 51 is provided with a central notch 52 extending inwardly from the free end thereof. Notch 52 effectively divides hook 51 into two sections 53, 54 of equal width. The width B of section 54 is slightly less than the width of mounting recess 46 of narrow circuit breaker 45.

As is best seen in FIGURE 7, when a pair of narrow circuit breakers 45 are mounted to hook 51, hook sections 53, 54 are each disposed in mounting recesses 46 of an individual circuit breaker 45. Since both ends of mounting recess 46 are closed, the load end of circuit breaker 45 is maintained against movement transverse to the plane in which circuit breaker 45 is pivoted during mounting thereof. The combination of two circuit breakers 45 is held in a central position with respect to mounting hook 51, so that the possibility of adversely affecting the circuit breaker line connection is substantially eliminated.

Thus, this invention provides a novel mounting hook construction whereby either narrow or wide circuit breakers may be mounted in the same panelboard with the load ends locked in place. The narrow circuit breakers may be of identical external construction, each provided with mechanically independent housings, and there is no necessity for mechanically securing the narrow circuit breakers to one another at the load ends thereof.

Although the invention herein has been described in connection with an exemplary embodiment, it is to be understood that variations and modifications may be made therein without departing from the spirit and scope thereof, as defined in the following claims.

I claim:

1. A panelboard comprising an electrically energizable first means and a second means comprising a mechanical retainer for a circuit breaker load side and a point about which a circuit breaker line terminal is pivotable in a plane into engagement with said first means, said first and said second means cooperating to define a first location for mounting of a wide circuit breaker, said second means including a plurality of selections for mounting first and a second identically constructed narrow circuit breakers at said first location, said plurality of sections locking said first and second narrow circuit breakers against movement transverse to said plane; adjacent ones of said section being spaced by a notch.

2. A panelboard comprising an electrically energizable first means and a second means comprising a mechanical retainer for a circuit breaker load side and a point about which a circuit breaker line terminal is pivotable in a plane into engagement with said first means, said first and said second means cooperating to define a first location for mounting of a wide circuit breaker, said second means constructed to lock a first and second identically constructed narrow circuit breakers at said first location, against movement transverse to said plane; said second means comprising a hook adapted to be received by a circuit breaker mounting recess of a wide circuit breaker; said hook being divided into a plurality of sections separated by notch means communicating with an edge of said hook, each of said sections adapted to be received by a circuit breaker mounting recess of a narrow circuit breaker and provide means to pivot said narrow circuit breakers at said first location, in planes parallel to said previously recited plane.

3. A panelboard comprising an electrically energizable first means and a second means comprising a mechanical retainer for a circuit breaker load side and a point about which a circuit breaker line terminal is pivotable in a

plane into engagement with said first means, said first and said second means cooperating to define a first location for mounting of a wide circuit breaker, said second means constructed to lock a first and a second identically constructed narrow circuit breaker at said first location against movement transverse to said plane; said second means comprising a hook adapted to be received by a circuit breaker mounting recess of a wide circuit breaker; said hook being divided into a plurality of sections separated by notch means communicating with an edge of said hook, each of said sections adapted to be received by a circuit breaker mounting recess of a narrow circuit breaker and provide means to pivot said narrow circuit breakers at said first location, in planes parallel to said previously recited plane; said third means comprising a central notch in an edge of said hook positioned closest to said first means.

4. A panelboard comprising an electrically energizable first means and a second means for mechanically retaining a circuit breaker load side and providing pivot means about which a circuit breaker load side is pivotable into operative engagement with said first means; said first and said second means having a plurality of sets of cooperating formations each defining a location where either a single wide circuit breaker or a pair of narrow circuit breakers in adjacent side by side relationship may be mounted; the cooperating formation in each set for the second means comprising a first and a second section separated by a notch; said first and said second sections being spaced from one another within the limits defined by its respective location, and each being adapted to be received by a mounting recess, closed at both ends, of a narrow circuit breaker; said first and second sections being positioned so that both can at the same time be received by a mounting recess of a wide circuit breaker.

5. A panelboard comprising an electrically energizable first means and a second means for mechanically retaining a circuit breaker load side and providing pivot means about which a circuit breaker load side is pivotable into operative engagement with said first means; said first and said second means having a plurality of sets of cooperating formations each defining a location where either a single wide circuit breaker or a pair of narrow circuit breakers in adjacent side by side relationship may be

mounted; the cooperating formation in each set for the second means comprising a first and a second section separated by a notch; said first and said second sections being spaced from one another within the limits defined by its respective location, and each being adapted to be received by a mounting recess, closed at both ends, of a narrow circuit breaker; said first and second sections being positioned so that both can at the same time be received by a mounting recess of a wide circuit breaker; said cooperating formation in each set for the second means comprising a hook whose free end extends toward said first means.

6. A panelboard comprising an electrically energizable first means and a second means for mechanically retaining a circuit breaker load side and providing pivot means about which a circuit breaker load side is pivotable into operative engagement with said first means; said first and said second means having a plurality of sets of cooperating formations each defining a location where either a single wide circuit breaker or a pair of narrow circuit breakers in adjacent side by side relationship may be mounted; the cooperating formation in each set for the second means comprising a first and a second section; said first and said second sections being spaced from one another within the limits defined by its respective location, and each being adapted to be received by a mounting recess, closed at both ends, of a narrow circuit breaker; said first and second sections being positioned so that both can at the same time be received by a mounting recess of a wide circuit breaker; said cooperating formation in each set for the second means comprising a hook whose free end extends toward said first means; said first and said second sections comprising portions of said hook separated by a notch communicating with an edge of the hook positioned closest to said first means.
